UNITED STATES PATENT OFFICE.

PETER C. GREENAWALT, OF READING, PENNSYLVANIA, ASSIGNOR OF ONE-HALF TO L. B. WISMER, OF SAME PLACE.

DESIGN FOR A LEAF FOR HINGES.

SPECIFICATION forming part of Design No. 32,818, dated June 12, 1900.

Application filed May 11, 1900. Serial No. 16,373. Term of patent 14 years.

To all whom it may concern:

Be it known that I, PETER C. GREENAWALT, a citizen of the United States, residing at Reading, in the county of Berks and State of Pennsylvania, have invented and produced a new and original Design for a Leaf for Hinges; and I do hereby declare the following to be a full, clear, and exact description of the same, reference being had to the accompanying drawings, forming a part thereof.

In the accompanying drawings, Figure 1 is a perspective view of one of the members of a blind-hinge embodying my design. Fig. 2 is a perspective view looking at the same from the rear.

The leading feature of my design consists of a suitable body portion provided with attaching-holes, an outwardly-extending projection, and a butt provided with an upwardly-extending pintle, which butt is provided with an entering slot or recess in line with the pintle and with engaging shoulders on both sides of the pintle at the lower end thereof.

1 in the drawings represents the main body portion of my hinge provided with securing-holes 2, with an outwardly-extending engaging projection 3, and also with a butt 4, which latter is provided with an upwardly-extending pintle 6 and a vertically-arranged slot or recess 7 at the lower end of the pintle and in line with the same. The butt is also formed with engaging shoulders 8 and 9, which are arranged on both sides of the pintle at the lower end thereof, said shoulders being bevelled, as at 8^a and 9^a.

What I claim is—

The design for a leaf of a hinge, substantially as herein shown and described.

In testimony whereof I hereunto affix my signature in presence of two witnesses.

PETER C. GREENAWALT.

Witnesses:

L. B. WISMER,
S. P. FETTER.
